Leo J. Maffei, New Britain, Conn., assignor to The
American Hardware Corporation, New Britain, Conn.,
a corporation of Connecticut

Filed Dec. 5, 1962, Ser. No. 72,723

Term of patent 14 years

(Cl. D10—8)

FIG. 1 is a perspective view of the pull handle embodying my new design, taken from the right-hand side thereof.

FIG. 2 is a perspective view of said pull handle, taken from the left-hand side thereof.

FIG. 3 is a perspective view of said pull handle, taken from the rear thereof.

FIG. 4 is a side elevational view of the pull handle embodying my new design, illustrating the left-hand side thereof.

FIG. 5 is a front elevational view of said pull handle.

FIG. 6 is a top plan view of said pull handle.

FIG. 7 is a side elevational view of said pull handle, illustrating the right-hand side thereof.

FIGS. 8 to 11 are sectional plan views of said pull handle taken, respectively, on lines 8-8 to 11-11 of FIG. 5. FIGS. 4 to 7 are shown on a smaller scale than FIGS. 1 to 3, and FIGS. 8 to 11 are enlarged views.

I claim:

The ornamental design for a pull handle, substantially as shown.
